UNITED STATES PATENT OFFICE.

JAMES C. WALKER, OF WACO, TEXAS.

ROTARY ENGINE.

SPECIFICATION forming part of Letters Patent No. 615,597, dated December 6, 1898.

Application filed May 4, 1898. Serial No. 679,659. (No model.)

To all whom it may concern:

Be it known that I, JAMES C. WALKER, residing at Waco, in the county of McLennan and State of Texas, have invented certain new 5 and useful Improvements in Rotary Engines, of which the following is a specification.

This invention, which relates generally to that class of rotary engines having concentric pistons, particularly refers to improvements on the engine mechanism disclosed in my Patents Nos. 515,631, 611,535, and 611,536, the primary purpose of this invention being to provide certain improvements in the detail construction and arrangement of the parts 10 constituting the complete engine, whereby the same is simplified and rendered the more stable and effective in its operation.

This invention also comprehends certain improvements in the steam-cut-off-valve-operating devices, whereby to render them capable of use in combination with a sliding abutment-operating mechanism embodying the same general features of construction as those disclosed in my other patents referred to, or 15 with gravity cut-offs automatically operating within the steam or piston chamber.

In its subordinate features this invention embodies the peculiar combination and detail arrangement of parts such as will be first described in detail and then be specifically pointed out in the appended claims, reference being had to the accompanying drawings, in which—

Figure 1 is an elevation of my improved rotary engine, parts being broken away to the more clearly illustrate my invention. Fig. 2 is a detail section on the line 2 2 of Fig. 1. Fig. 3 is an enlarged section of the cut-off-valve-operating mechanism. Fig. 4 is a vertical section taken on the line 4 4 of Fig. 1. Fig. 5 is a detail view of the reversing devices hereinafter referred to. Fig. 6 is a plan view of one of the valve-operating shifting disks. Fig. 6^a is a section on the line a a, 45 Fig. 6. Fig. 7 is a view of a modified construction of my improved engine mechanism. Fig. 8 is a section taken practically on the line 8 8 of Fig. 7.

Referring to the drawings, and particularly 50 to Figs. 1 to 6, by letters of reference, B B' B' B³ represent the cylinders; A A' A² A³, the bore or steam-chambers thereof; a a' a² a³,

the sliding abutments or valves, and a⁴ a⁵ a⁶ a⁷ the slide-casings, all of which, as also the pistons P, connected to the shaft C, are constructed and operated substantially as the like parts in my other patents referred to. 55

In the present construction the slide-valves are operated similar to the slide-valves in my other patents; but in this case the arrangement of the operating-levers is somewhat different, such valve-operating mechanism being the same for each cylinder, the several mechanisms being, however, so arranged as to operate alternately, as before. 60

As the several slide-valve-operating mechanisms are constructed and operate alike, I shall describe one set in detail only and refer to the others hereinafter in a general way.

Each slide-operating mechanism comprises 70 a disk b, fixedly secured to the shaft C, provided with a radially-projecting cam b', and the peripheral edge of such disk operates within a narrow casing b², secured to the side of the cylinder, in which is held for vertical 75 reciprocation a carriage or frame comprising a sector-piece b³, carrying friction-rollers b³⁰ at the ends, which engage the side walls of the casing b², and the rod b⁴, secured to the sector-piece b³, braced by the side arms b²⁰, and 80 having its upper end pivotally joined to a straddle-frame c', having side arms c³ c², fixedly secured to a sleeve c¹⁰, held to rock on a short shaft c, journaled in the bracket c²⁰, and having its outer end pivotally secured to the 85 lower end of the lift-links c⁴ c⁵, connected to the cross-head c⁶ of the lift-rod a¹⁰, secured to the slide-abutment, as clearly shown.

So far as described it will be readily observed that by means of the lever devices and 90 the disks b the several slide-abutments will be elevated at predetermined intervals by the rods b⁴ and drop down by gravity when the disk members b⁷ pass from under the sector members b³. As before stated, the several 95 abutment-slide-operating devices are arranged to operate quarterly, the purpose being to subject the axle to a direct impact at four radial points, the disks b for the cylinders B² B² being so set and fixed on the main 100 shaft C, and the two disks d and r so set and fixed on the shaft s², that the former will operate the abutment-valves and the latter the inlet-valves, so that the shaft C shall be sub-

ject to impulses of live steam at every quarter-turn four times in each revolution.

The steam-cut-off-valve-operating device the peculiar construction of which forms the 5 essential feature of this invention embodies in its generic features the disk-operated valve-shifting devices disclosed in the other Patents Nos. 611,535 and 611,536, heretofore referred to.

10 In the present construction the cut-off valve-operating devices embody the shaft e^2 , vertically disposed between the cylinders B' B^2 , the lower end of which has a stepped and ball bearing on the bracket X , while the upper end is braced in the cross member m . The lower end of the shaft e^2 carries a gear e' , which meshes with the drive-gear e , while on the upper end of such shaft is mounted a ball-governor, consisting of the ball-rod w^2 , 15 hinged to the crown-piece w^3 and carrying the balls w , and the link-rods w^4 , connecting the arms w^2 with the collar w' , reciprocally held on the shaft e^2 .

20 e^7 indicates a rack-bar secured to and held pendent from the collar w' , the lower end of which is guided in the bracket e^6 on the shaft e^2 . This bar is movable through slots in a pair of horizontally-disposed disks r and d , disposed one above the other and each secured to the shaft e^2 to turn therewith. These disks carry governor-adjusted valve-shifting devices of similar construction and operating alike.

25 The disk d has a shaft e^{12} , carrying a pinion e^8 , held to mesh with the rack-bar e^7 , and a larger cog-wheel e^{10} , held to mesh with the lower rack-face of an annulus d' , rotatable in a suitable seat or guideway d^2 on the upper face of the disk, the disk r having a similar 30 shaft r^{12} , having gears r^r r^s for transmitting motion to the rack annulus or ring r^6 . Each disk has an annular flange and a fixed cam r^{13} d^8 , forming a part thereof, in the nature of a $>$ -shaped inwardly-projecting member, 35 the purpose of which is to alternately engage the pull-rods o r^8 , which connect with the cut-off valves for the cylinders B^3 , and the rods d^4 d^9 , which connect with the cut-off valves of the cylinders B^2 and B' , the rods o 40 and r^8 , which are operated by the upper disk, having angle members o^x r^x , with which the flange and cam r^{13} are adapted to engage, the free end of the rod r^8 having pivotal connection with the crank r^9 of the rock-lever 45 r^{11} , carrying valve r^{10} , while the free end of rod o is connected to the crank o' of the rock-lever o^2 , carrying the valve o^3 for the cylinder B . The rods d^4 d^9 are likewise connected to the rods d^6 d^{11} , carrying, respectively, the 50 valves d^{12} d^7 for the cylinders B^2 B' .

55 r^7 indicates a cut-off extended radially from the post e^2 , to which it is pivotally attached by the loose ring member r^{20} . This cut-off is fixedly connected to the upper face of the annulus r^6 , and has its outer portion projecting beyond such annulus and terminating in a double cam (V-shaped) end, the bearing-faces

of which are inclined reversely to the cam r^{13} , fixedly formed on the disk r . The under side of the cut-off has a clasp r^{15} , (see Fig. 6,) 70 which extends on the slot beneath the rim r^5 loosely, so as not to interfere with the sliding of the cut-off, but holds it in position against the thrust of the end of the inlet-valve levers r^8 and o . (See Fig. 3.) The lower 75 disk d is also provided with a radial cut-off d^8 , which operates like the cut-off r^7 and is adjusted by the operation of the shaft e^{13} .

80 So far as described it will be readily seen that as the shaft e^2 is driven from the main drive-shaft C the two disks d and r will rotate therewith, and in consequence the arms o r^8 d^9 d^4 will be intermittently drawn in by the fixed cam members of the said disks d and r , and thereby open the inlet-valves and such arms o r^8 d^9 d^4 be moved back by the cut-offs r^7 d^8 to close the respective valves connected therewith, and by reason of engagement with the adjustable cut-offs r^7 d^8 the length of time in which the valves of the several cylinders B' B^2 B^3 are held open depending on the correlation of the movable cut-offs with the fixed cams on the disks r and d , which is dependent upon the speed of the engine. Thus should the engine have an accelerated 95 speed the governor-arms w^2 will be swung outwardly proportionately, and in consequence raise the rack-bar e^7 , and thereby cause the annular rack members to which the cut-offs are attached to move such cut-offs toward the fixed cam, and thereby shut off supply of steam quickly to decrease the speed of the engine, it being understood that in case the engine slows up the arms w^2 will be caused to contract, and thereby operate 100 the rack e^7 and the annular rack-rings d' and r^6 in a reverse direction to move the cut-offs r^7 d^8 away from the fixed cams and proportionately lengthen the time of feed of the live steam to the several cylinders and provide a 105 positive, accurate, and uniform means for effecting the steam-supply and governing the speed of the engine.

110 It will be readily understood by reference to Fig. 1 that the mechanism for shifting the abutment-slides and the means for operating the steam-cut-off devices are relatively so arranged that the slides will be properly lowered immediately after the pistons pass under them, so as to provide an abutment for 115 the live steam which enters at the proper time between such abutment and the piston.

120 The operation of my improved engine is best explained as follows, reference being particularly had to cylinders B^2 and B^3 : When the shaft C is in motion, the disk members b , through their projections b' , will at a proper time engage the crescent members b^8 of the lift-rods b^4 and elevate them, and thereby rock the frames to which they connect, which 125 in turn lift the abutment-slides, which slides are held to their elevated position during the engagement of the members b' with the crescent b^8 , which provides ample time for the

piston to pass under the abutment-slide, the relation of the members b^3 and b' being such that as soon as the piston passes under the said slides such abutment-slides will immediately drop by gravity, it being understood that spring devices (not shown) may be provided to assist such downward movement of the abutment-slides. During this operation the shaft e^2 carries the disks d and r through their cams $r^{13} d^8$, which are alternately arranged to move the arms $r^8 o d^9 d^4$ to rock the levers $d^6 d^{11} r^{11} o^2$, so as to open up the steam-ports, which are held open until the radially-disposed cut-offs engage them and move them back to their closing position, it being understood that as the cut-offs are governed in their set position by the automatic governor mechanism heretofore described a uniform and regular feed of the steam to the cylinders is maintained each quarter-turn of the shaft C.

It is manifest the several cylinders $B' B^2 B^3 B^4$ have suitable exhausts arranged in advance of the abutment-slides for the exhaust of the spent-steam charge before the piston passes under the abutment-slides, as shown at E X in Fig. 2.

In Figs. 7 and 8 I have shown my improved valve-operating devices in connection with gravity abutment-valve mechanisms set to their open position by direct contact with the piston. In such form of mechanisms A indicates the cylinder-bore, P the piston, and a^2 the abutment-valve, which is hinged at a^4 , the hinge edge being fitted to the socket to permit the body of the valve a^2 fitting firmly on the seat a^6 , formed in the crown of the bore A, said valve being so adjusted that when raised by the passing piston it will occupy the position shown in dotted lines in Fig. 8. y indicates the abutment cut in the sides of bore A, on which a^2 rests steam-tight when it is down, as shown in Fig. 8. a^8 indicates a cut-away portion on the bore A for the free lift of the valve a^2 . o^4 indicates the inlet-ports, which are arranged directly over the valve a^2 , over which the rotary valves o^3 operate and which have their crank-arms o^9 connected with the levers $d^9 o r^3 d^4$, which levers are operated the same as the corresponding levers shown in Figs. 1 and 2.

The cylinder-disks D revolve between the two half-sections of each cylinder and snugly close the intervening annular space, (indicated by $a a'$.) Each of the disks d has an integral or attached piston P, having a front beveled impact edge p , so inclined as to first engage the lower edge of the abutment a^2 .

The exhaust b^3 of each cylinder is so located in relation to the abutment-valve a^2 that the rear edge of the piston will be passing the outer edge of the port as such piston begins to lift the abutment, whereby to instantly release the steam as the abutment is engaged and to relieve such abutment from all back pressure, the piston having then only the weight of the abutment-valve a^2 to

raise, it being obvious that the instant the rear edge p^4 of the piston passes the lower end of the abutment-valve a^2 such valve will fall back by gravity and close the bore, it being held down by the live steam, which, owing to the set of the valves o^3 and their operating mechanism, enters the cylinder-bore the instant the valve a^2 drops, the thrust of such steam on the abutment and the back of piston serving to impel such piston and the disk D rapidly forward. This latter arrangement of the abutments simplifies the construction of my complete machine, as it dispenses with the intermediate connections operated by the shaft C for elevating the abutment.

In my present form of engine mechanism the drive-shaft C is connected with a supplemental drive-shaft by means of suitable reversing mechanism, the construction of which is best illustrated in Fig. 5, and comprises the shaft x^6 , journaled in suitable bearings x^7 and provided with a non-circular portion x^5 , on which is mounted an endwise-movable clutch-sleeve x^{14} , operated by means of the shifting-lever x^{10} , having beveled gears $x^1 x^2$ at the opposite ends adapted to be alternately brought into mesh with the beveled gear x^3 on the engine-shaft C, the said shaft x^6 having loose and fast pulleys P^6 .

In the practical application of my improvements it is intended to inclose the boiler and as much of the engine as may be practicable in a sheet-metal casing, asbestos-lined, to utilize the radiation and keep the entire structure at a uniform temperature.

From the foregoing description, taken in connection with the accompanying drawings, it is thought the complete operation and advantages of my improvements will be readily understood.

Having thus described my invention, what I claim, and desire to secure by Letters Patent, is—

1. In a machine of the character described, in combination with the inlet-port and the cut-off valves therefor; of mechanism for operating such valves comprising a drive-shaft geared with the engine-shaft; a disk mounted on the drive-shaft to rotate therewith, having a fixed cam to move the inlet-valves in one direction; a ball-governor mounted on the drive-shaft; a cut-off member mounted on the disk to rotate therewith, but having movement independent thereof, said cut-off member operating to move the valve in a direction reverse to that of the fixed cam on the disk and a rack or pinion mechanism operated by the shifting of the ball-governor held to engage with and shift the cut-off member, as specified.

2. In a rotary engine as described; the combination with the valve-operating levers and the engine-shaft; of the shaft e^2 , the disks d and r , rotatable therewith, said disks having each a fixed cam, and an annular ring held for axial movement independent of the shaft e^2 , a governor mechanism carried on the shaft

*e*³ for connection with the annular rack-rings and adapted to shift such rings in reverse directions by the variable speed of the engine, and cut-off levers secured to the said rings, all being arranged substantially as shown and described.

3. In an engine as described; the combination of the valve-operating levers, the engine-shaft; the shaft *e*³ geared therewith, the ball-governor devices, the vertically-reciprocal rack *e*⁷, connected to such governor devices,

the disks *d* and *r*, said disks having annular rack-ring members *r*⁶ *d*¹, the shafts *e*¹² *r*¹², connecting such members *r*⁶ *d*¹, with the rack *e*⁷, and the cut-offs *r*⁷ *d*³, secured to such members *r*⁶ *d*¹, all being arranged substantially as shown and described. 15
